PAPER CUP

Herman Carew, Easton, Pa., assignor to Individual Drinking Cup Company, Inc., Easton, Pa., a corporation of Pennsylvania

Application August 22, 1930, Serial No. 477,098

1 Claim. (Cl. 229—1.5)

My invention relates to new and useful improvements in receptacles and more particularly to paper cups or the like intended for but a single use and adapted to be nested in stack formation so that the terminal cup may be withdrawn for use.

The principal object of the invention resides in the provision of a receptacle of the character described which is relatively simple and inexpensive in construction, being formed of relatively light material, and of a construction adapting a relatively large number to be nested in a relatively small stack thereby facilitating their use in dispensing machines and making it unnecessary for the attendant to frequently refill or replenish the dispensers.

Another object consists in providing a receptacle of the character described having advantages of both the cylindrical and flat types previously used, the same being provided with a round normally open mouth portion and a body portion which is of substantially wedge-shape tapering downwardly to provide a flat relatively wide bottom adapted to be engaged by the fingers when removing the terminal receptacle from a stack and while using.

A further object of the invention resides in forming the receptacle or cup from a single piece of material or blank adapted to be folded on a transverse or horizontal line to provide a body portion with a closed bottom, the sides of the body being closed by folding edge portions of the material or blank, and securing said folded edge portions to the body.

Still another object of the invention consists in forming a receptacle or cup from a single piece or blank of material and folding the same in a novel manner to provide a body portion with a tightly closed bottom and side edges thereby preventing leakage while the receptacle or cup is in use.

With the above and other objects in view, which will appear as the description proceeds, my invention consists in the novel details of construction, and arrangement of parts, described in the following specification and illustrated in the accompanying drawings, and while I have illustrated and described the preferred embodiments of the invention, as they now appear to me, it will be understood that such changes may be made as will fall within the scope of the appended claim.

In the drawings:—

Fig. 1 is a perspective of a completed cup or receptacle.

Fig. 2 is a side elevation of a completed receptacle or cup.

Fig. 3 is an elevation at right angles to that disclosed in Fig. 2.

Fig. 4 is a top plan.

Fig. 5 is a plan of a blank from which the receptacle or cup is formed.

Fig. 6 is a perspective showing the initial fold of the blank.

Fig. 7 is a fragmental detail showing a vertical section through the bottom portion of the receptacle or cup; and

Fig. 8 is a horizontal section on the line 8—8 of Fig. 7.

In the drawings *a* indicates a blank of the material, preferably paper, from which the receptacle or cup is to be formed, this blank being of a shape or form to provide the oppositely directed sectors or keystone-shaped portions 1 and 2, a flange or extension 3 being formed on one longitudinal edge of the portion 1 while a flange or extension 4 is formed on the opposite longitudinal edge of the portion 2. In forming the receptacle or cup the blank is adapted to be initially folded on the transverse or horizontally extending line 5 and 60 as shown more particularly in Fig. 5 of the drawings the inner end of the flange or extension 3 on the portion 1 extends beyond the fold point 5 to provide the section 6 merging with and forming a part of the portion 2. Likewise the inner end 70 of the flange or extension 4 of the portion 2 extends beyond the fold point 5 to provide the portion 7 merging with and forming a part of the portion 1 of the blank.

As previously stated in forming the receptacle 90 or cup the blank is initially folded on the line 5 to form a closed bottom 8 for the completed receptacle or cup and in this initial folding the portion 6 will extend parallel with the flange or extension 3 and the portion 7 will extend parallel with 95 the flange or extension 4. The flanges or extensions 3 and 4 as well as the portions 6 and 7 thereof are coated on one side with an adhesive as is shown in the drawings and when the blank is folded the portions 6 and 7 will adhere to their 100 respective parallel flanges or extensions 3 and 4. In folding along the line 5 the edge of the portion 1 not provided with the flange or extension will engage the opposed portion 2 along the line 9 of Fig. 5, as shown more particularly in Fig. 6 105 of the drawings, and the edge of the portion 2, not having the flange or extension, will engage the opposed portion 1 along the line 10 of Fig. 5, as shown more particularly in Fig. 6 of the drawings.

After the initial fold of the blank above described the lower portion of the flange or extension 3 will be folded over the outer face of the portion 2 and secured thereto by the adhesive. 5 The lower portion of the flange or extension 4 will be folded over the outer face of the portion 1 and secured thereto by the adhesive. It will be understood and seen that the portions 6 and 7 are folded with the flanges 3 and 4, respectively, 10 and when the flanges or extensions are folded and secured in position the portions 6 and 7 provide a tight closure adjacent the bottom of the receptacle or cup and the folding and securing of the flanges or extensions form tight seams at 15 the sides of the receptacle or cup. As shown more particularly in Figs. 1 and 2 of the drawings the side seams extend at an angle from the true vertical with the bottom edges of the seams being directed inwardly towards the vertical center of opposed sides of the receptacle or cup, the lower ends 20 of the flanges or extensions extending upwardly at an angle, as shown more particularly at 11 and 12 in Figs. 1 and 2 of the drawings. The angles at which the flanges or extensions are positioned aid in forming a tight closure at the bottom of the 25 receptacle or cup.

From the above detailed description it is thought that the manner in which the receptacle or cup is formed from the blank of material will be clearly understood. In the folding of the blank 30 and securing of the side edges, it will be seen that I have provided a receptacle having a round normally open mouth portion and a body portion which is of substantially wedge-shape tapering downwardly to provide a flat relatively wide bottom adapted to be engaged by the fingers when 35 removing a terminal receptacle or cup from a stack thereof and while using. A cup or receptacle of this formation has the advantages of both the well-known types of cylindrical and flat cups. 40 My cup or receptacle is of a formation whereby a relatively large number may be nested in a

relatively small stack. This is of particular advantage where the cups are to be dispensed from a dispensing machine and obviates the necessity of an attendant frequently replenishing or refilling. The terminal receptacle or cup may be removed from the stack, as previously stated, by grasping the relatively wide flat bottom edge and in withdrawing the terminal cup from the stack and necessary compression caused by engagement with the fingers will have a tendency to slide the terminal cup from the next cup in the stack thereby facilitating its removal. The overlapped and adjoining portions of the walls or portions 1 and 2 being continuous and free from creases or folds serve as reinforcements tending to resist collapse or closing of the mouth portion. By forming my receptacle or cup of relatively light material and of a single blank or piece of material the same may be cheaply made and by folding the blank on a transverse horizontal line as I have described a water-tight bottom is provided to prevent leakage. The formation of the portions 6 and 7, extending beyond the fold line of the blank also aids in forming a tight closure at each side of the bottom to prevent leakage at the bottom adjacent the side 100 seams.

Having fully described my invention what I claim as new and desire to secure by Letters Patent is:—

A paper drinking cup having an open self-extended mouth and a downwardly tapered rounded body terminating in a wedge-shaped bottom, said cup being formed from a single piece of material folded on a medial transverse line to provide opposite wall portions, edges of the wall portions 110 being overlapped and secured together, the overlapped edges of the wall portions providing longitudinal reinforcements throughout the length of the body, and at the sides thereof, the reinforcements being positioned on opposite sides of the 115 medial fold line of the material.
